UNITED STATES PATENT OFFICE.

JAMES J. WOOD, OF FORT WAYNE, INDIANA, ASSIGNOR TO THE GENERAL ELECTRIC COMPANY, OF NEW YORK.

ARMATURE FOR MULTIPOLAR DYNAMOS.

SPECIFICATION forming part of Letters Patent No. 658,100, dated September 18, 1900.

Application filed June 14, 1898. Serial No. 683,406. (No model.)

To all whom it may concern:

Be it known that I, JAMES J. WOOD, a citizen of the United States, residing at Fort Wayne, in the county of Allen and State of Indiana, have invented certain new and useful Improvements in Armatures for Multipolar Dynamos, of which the following is a specification.

This invention provides improved means for ventilating armatures for multipolar dynamo-electric machines in order to prevent overheating of the coils. To this end I provide ventilating-spaces between the coils and core and the spiders, so that currents of air may enter inside the core and circulate through air-ducts against the core and around the coils.

Figure 1 of the accompanying drawings is a vertical diametrical section of an armature and commutator embodying my invention. Fig. 2 is a half end elevation of the left-hand spider in Fig. 1 viewed from the commutator end. Fig. 3 is a sectional elevation viewed from the left in Fig. 1, the upper left-hand quarter being an elevation, the upper right-hand quarter a section on the line 3^a in Fig. 1, the lower right-hand quarter a section on the line 3^b, and the lower left-hand quarter a section on the line 3^c. Fig. 4 is a fragmentary section, being an enlargement of the upper part of Fig. 1, showing one of the ventilating-gaps in the core. Fig. 5 is an enlarged plan of part of the periphery of the armature, showing one of the ventilating-gaps with part of the winding omitted. Fig. 6 is a fragment of the core-punching at a ventilating-gap, showing the twisting of its teeth. Fig. 7 shows one of the spacing-pieces removed.

In the particular construction of armature illustrated the armature-shaft (not shown) passes through a sleeve *d*, forming the hub of the fixed armature-spider *A*, the removable spider *A'* being slipped over this hub. Between these two spiders a core *B* is mounted, the core being held in place and the spiders united by means of bolts *CC*, passing through holes *e e* in the spiders and engaging holes or notches in the core. The core *B* is laminated, being made up of punchings of thin sheet-steel in the usual manner, and is peripherally

slotted to receive the winding in the manner common to iron-clad armatures. The armature-winding is lettered *D* and is of the usual type, one side of each coil being carried through the inner half of a core-slot, while the opposite half thereof passes through the outer half of another core-slot removed from the first a distance depending upon the number of poles in the multipolar field-magnet, so that one side of the coil will be passing through a positive field while the other side is passing through a negative field, as is well understood. The intermediate or end portions of the coils are carried beyond the ends of the core sufficiently far to accommodate their oblique portions, these outlying portions of the winding being supported by flanges *E E'* on the respective spiders. The flange *E* on spider *A* is cylindrical, the commutator connections being made with the coils at its outer edge, as indicated. The flange *E'* is turned outwardly at its outer side, as shown at *E'*, to protect the bends of the winding.

According to my invention I provide against overheating of the core and winding by means of ventilating spaces or ducts, through which currents of air may flow. The core punchings or laminæ may be separated at intervals to form ventilating-spaces or air-ducts *f f*, through which air may circulate to cool the core. At opposite ends of the core the end plates or rings of the spiders are spaced mainly apart from the core by the provision of ribs *g g* thereon, which ribs extend radially and support the end laminæ of the core at frequent intervals, leaving between them ventilating-spaces or air-ducts *h h* for circulation of currents of air. These ribs extend not only along the faces which are against the ends of the core, but are also provided on the outer surfaces of the flanges *E E'*, these continuations of the ribs being lettered *g' g'*. The upper half of Fig. 1 is in section through the ribs *g g'*, while the lower half of this figure is in section between the ribs, showing the ventilating-spaces *h h*. The arrows indicate the direction of the currents of air which are drawn into the interior of the armature through openings *i i* in the spiders and which pass radially outward through the core-spaces *f f* and through the end ventilating-ducts *h h*.

The circulating air thus cools the core and also by flowing around the end portions of the coils or winding cools the latter. The ribs $g' g'$ are frequent enough to give adequate support to the outlying portions of the winding, so that my mode of ventilation does not detract from the adequate and firm support of the coils, which are bound down onto the flanges by outer bands in the usual manner. The outturned flange E^2 at one end serves to direct the air-currents outwardly. It is preferable to form also ventilating gaps or spaces ff through the body of the core, which may readily be done by interposing a series of spacing-pieces $F F$ at intervals, as shown in Fig. 3, to hold apart the core-laminæ within the winding. These spacing-pieces, of which one is shown separately in Fig. 7, are made, preferably, of brass, with radial portions j and connecting-pieces k and with flat faces ll at intervals to seat against the opposite laminæ. To prevent the ventilating-spaces being closed by the teeth between the slots containing the windings, the teeth of one lamina may be twisted or turned crosswise, as shown at m in Figs. 4, 5, and 6, which will effectually hold these spaces open.

I claim as my invention the following-defined novel features, substantially as hereinbefore specified, namely:

1. An armature comprising end spiders and an intermediate core and a winding extending across the periphery of the core and overlying the surface of the spiders, and provided with ventilating air ducts or channels extending outwardly between the spiders and core and then laterally along the spiders beneath the winding, substantially as described.

2. An armature having a laminated core clamped between end spiders, said spiders formed with ribs at intervals in contact with the ends of the core, said ribs extending from the inner part of the core outwardly to the exterior thereof and forming between said

ribs ventilating-passages $h h$ through which air may circulate from the interior of the core to the exterior of the armature.

3. An armature having a laminated core clamped between end spiders, having outturned flanges for supporting the outlying portions of the winding, and having ventilating-spaces between said flanges and the winding for cooling the latter.

4. An armature comprising end spiders and an intermediate core, and a winding extending across the core and overlying the surface of the spiders, said spiders having ribs on their inner faces against the core leaving outwardly-extending air-ducts, and having ribs on their outer portions beneath the overlying winding forming laterally-extending air-ducts communicating with the outwardly-extending air-ducts.

5. An armature comprising end spiders and an intermediate core, and a winding extending across the core and overlying the surface of the spiders, and provided with ventilating air-ducts extending outwardly between the spiders and core, and then laterally along the spiders beneath the winding, and an annular flange at the end of one spider for directing the air-currents outwardly.

6. An armature comprising end spiders AA' , with a laminated core B clamped between them, said spiders formed with outturned flanges $E E'$, having ribs $g g$ on their inner faces against said core, and ribs $g' g'$ on the outer portions of said flanges, whereby between said ribs are formed ventilating-spaces $h h$ for cooling the core and winding.

In witness whereof I have hereunto signed my name in the presence of two subscribing witnesses.

JAMES J. WOOD.
